(57) **CLAIM**

The ornamental design for a handleset, as shown and described.

DESCRIPTION

FIG. 1 is a top, front, right side perspective view of a handleset, showing my new design;
FIG. 2 is a bottom, front, left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof; and,

FIG. 9 is a top, front, right side perspective view of the handleset of FIG. 1 shown at a reduced scale and in a condition of use.

The broken lines in the drawings depict portions of the handleset that form no part of the claimed design. The broken lines showing the door in FIG. 9 depict environmental subject matter that forms no part of the claimed design.

1 Claim, 9 Drawing Sheets
